UNITED STATES PATENT OFFICE.

WILLIAM A. SCHRAUBSTADTER, OF ST. LOUIS, MISSOURI.

DESIGN FOR A FONT OF PRINTING-TYPE.

SPECIFICATION forming part of Design No. 25,389, dated April 14, 1896.

Application filed September 30, 1895. Serial No. 564,214. Term of patent 7 years.

To all whom it may concern:

Be it known that I, WILLIAM AUGUST SCHRAUBSTADTER, a citizen of the United States, residing at St. Louis, in the State of Missouri, have invented and produced a new and useful Design for a Font of Printing-Type, of which the following is a specification, reference being had to the accompanying drawing, showing a part thereof.

The drawing shews a face view of a font of type comprising the upper and lower cases.

The leading feature of my design consists in the letters sloping at the angle shown in the drawing, preserving a script-like character.

What I claim is—

The design for a font of printing-type as herein shown and described.

WILLIAM A. SCHRAUBSTADTER.
